UNITED STATES PATENT OFFICE

LUCIFER J. MOST, OF KEARNY, NEW JERSEY

DESIGN FOR A MECHANICAL PENCIL

Application filed May 28, 1930. Serial No. 35,803. Term of patent 3½ years.

To all whom it may concern:

Be it known that I, LUCIFER J. Most, a citizen of the United States, and resident of 137 Seeley Avenue, Kearny, county of Hudson, New Jersey, have invented a new, original, and ornamental Design for Mechanical Pencil, of which the following is a specification, reference being had to the accompanying drawing, forming part thereof.

The figure is an elevation of a mechanical pencil showing my new design, in which a prismatic section is merged with bases of frustro-conical sections.

I claim:

The ornamental design for a mechanical pencil, as shown and described.

LUCIFER J. MOST.
